UNITED STATES PATENT OFFICE.

MURRAY CORRINGTON, OF NEW YORK, N. Y.

ENGINEER'S BRAKE-VALVE.

SPECIFICATION forming part of Letters Patent No. 762,865, dated June 14, 1904.

Application filed April 5, 1904. Serial No. 201,766. (No model.)

To all whom it may concern:

Be it known that I, MURRAY CORRINGTON, a citizen of the United States, residing at New York city, in the county and State of New York, have invented certain new and useful Improvements in Engineers' Brake-Valves, of which the following is a specification.

My invention relates to improvements in engineers' brake-valves forming part of an automatic fluid-pressure brake system for enabling an engineer to keep himself fully advised at all times concerning the exact conditions of pressure existing on the opposite sides of the equalizing-piston and to exercise a better control than he has heretofore been able to do over its movements.

Referring to the drawings, Figure 1 is a vertical section of a brake-valve having an equalizing-piston of substantially the same construction as that illustrated in my own United States patent, dated May 26, 1903, No. 729,044. Fig. 2 is a similar section of a brake-valve embodying the same general principles of construction as the United States patent issued 25 March 31, 1896, to George Westinghouse, Jr., No. 557,463. Figs. 3 and 4 are respectively plan or top views of the rotary valve-seat and valve of my said prior patent. Figs. 5 and 6 are respectively similar views of the corresponding valve-seat and valve of the said Westinghouse patent.

In all figures of the drawings the reference-numerals correspond so far as practicable with those employed in said prior patents, and the 35 description of the drawings and of the operations of the mechanism will not be repeated here except so far as necessary to the understanding of my within-described improvements, since such descriptions are so fully set out in said prior patents.

In both Figs. 1 and 2 the handle 7 is in full release position. In Fig. 1 pressure from the main reservoir flows through passages and ports 17, 27, and 30 into the train-pipe cavity 45 18 and thence through passage 71 to the under side of the piston 19 and through ports and cavities 42, 37, and 90 to the upper side of said piston. In Fig. 2 main-reservoir pressure flows through passages and ports 17, 27, 28,

29, and 30 into the train-pipe 18 and at the 50 same time through ports 31 and 32 to the upper side of piston 19, while train-pipe pressure flows to its under side through passage 71 and by passage 72 to valve 21. The more exact location of the ports and the course of the air 55 in flowing to the train-pipe in the Westinghouse device is seen in Figs. 5 and 6, supposing that the valve 5 is moved to the left and placed upon its seat, so that the line indicating the handle falls upon the line indicating "release" 60 position; but in order that this may be fully understood from looking at Fig. 2 I have represented the port or cavity 28 in the valve-seat partly diagrammatically by continuing it in dotted lines up to cavity 29 in the valve 5. In 65 both Figs. 1 and 2 the usual equalizing-reservoir is connected at 25 for the purpose of enlarging the capacity of piston-chamber 22 above the equalizing-piston, and the usual connections of the gages for indicating, respectively, main-reservoir pressure and train-line pressure are represented at 51 and 52.

It is to be understood that valve 5 of Fig. 4 is to be moved to the left and placed in position upon the valve-seat 6 of Fig. 3 and that Fig. 6 is to be similarly placed upon the valve-seat of Fig. 5. In Fig. 3 the ports 30, 33, 35, 38, 39, 42, 43, 44, and 90 correspond in position and function with the ports and passages similarly numbered in my said prior patent, 80 and the same is true of port 27 through the valve 5 and cavities 29 and 37 on its under face. The ports and passages 28, 30, 32, 33, 35, 36, 38, and 39 of Fig. 5, as well also as the ports and cavities 27, 31, 29, and 37 in the 85 valve 5 of Fig. 6, correspond in position and function with the ports and cavities similarly numbered in said Westinghouse patent. As the purpose and function of all these parts are so fully described in said prior patents, 90 I do not deem it necessary to repeat them here.

In both my own and the Westinghouse prior patent it will be seen on reference thereto that the under side of the equalizing-piston 19 is always exposed to pressure from the train-pipe and that the pressure is first admitted into the chamber at the lower nozzle or cavity of the

casing 2, whence it flows directly upward to the under side of the piston. The result both with my own and the Westinghouse device, particularly with the valve-handle in release position, is that the pressure flows from the main reservoir into the train-pipe 18 and thence against the under side of the piston more rapidly than pressure can get to the upper side of the piston and the equalizing-reservoir connected therewith, so that the higher pressure on the under side of the piston often lifts it upward, opens the passage 23, and permits the waste of considerable of the compressed air, which is needed to release brakes and charge the system for operation.

In the construction illustrated in Figs. 1, 3, and 4, as fully set forth in my said prior patent, in all positions of the valve 5 in which compressed air is admitted into the train-line 20 the cavity 37 in the valve keeps the piston-chamber 22 above the piston in communication with train-line 18 through ports 42 and 90. This happens whether the port 27 in the valve stands over port 30, port 33, or 25 port 43 in the valve-seat. In the construction of the Westinghouse device (illustrated in Figs. 2, 5, and 6) the chamber 22 above the piston is open to the main-reservoir pressure when the valve is in release position; 30 but it is open to train-pipe pressure by means of cavity 29 in the valve-connecting ports 30 and 36 in the valve-seat, the latter leading to the chamber 22, when the valve is in what is known as "running" position. For convenience of understanding and description I shall refer to the under side of the piston 19 as its train-pipe side and to the upper side of said piston as its reservoir side, and it is to be understood that in all cases where I 40 speak of "reservoir" or "reservoir-pressure" I refer to the equalizing-reservoir which is attached to the connection 25 unless some other reservoir is particularly designated.

45 In Fig. 1 it will be noticed that passage 44 enters the train-pipe chamber 18, and this corresponds exactly in function with the passage similarly numbered in my said prior patent, being the port through which pressure enters 50 the train-pipe after passing through the pressure-reducing or feed valve when valve 5 is in position for port 27 to stand over port 43. In Fig. 2 I have shown a similar passage 35, entering the casing 3 from the right, and this corresponds in function with the similar passage seen in dotted lines in Fig. 5, though not in the same relative positions in the two figures. For our present purposes the passages 44 and 35 in the two figures may be considered the equivalents of each other, being in each case the passage through which compressed air is admitted to the train-pipe after passing through the pressure-reducing or feed valve from the main reservoir, whereby the 55 train-pipe pressure may be held at a constant

point while the train is running, as fully explained in my own and the Westinghouse prior patents.

In order to effect my improvements and to embody the same in either of the types of 70 brake-valve illustrated in said prior patents, I employ the following construction: In Figs. 1 and 2 instead of admitting the compressed air first into the large nozzle or 75 chamber at the lower end of the casing 2 and then bringing it up against the piston 19 a passage 71 leads from the piston-chamber into the passage 18, through which the air flows on its way to the train-pipe proper in such relationship to the latter passage that as the air flows 80 toward the train-pipe it must flow across the end of the passage 71 in such manner as to tend to create a suction or draft downward through the passage or away from the train-pipe side of the piston. This will be effective 85 to a degree if the passage 71 stands at right angles to the passage leading to the train-pipe; but it is more effective if it enters the train-pipe passage at an acute angle from above, as seen in Figs. 1 and 2. It will be observed that 90 no matter what position the valve occupies for admitting air into the train-pipe with either device the air must always flow across the outer or lower end of the passage 71, and I have found in practice that this construction 95 is absolutely effective in holding the equalizing-piston down and keeping the passage 23 closed and preventing waste of the compressed air needed to release and recharge the 100 system and no matter whether the engine-brakes alone are being operated or the brakes on engine and one or more cars.

To enable the engineer to know at all times the conditions of pressure above and below the equalizing-piston, a small channel 91 is 105 cut in the face of the valve-seat of Fig. 3 and a port 92 is drilled downward to connect with a passage 93 to the outside of the casing, from which a pipe 94 leads to one hand of the usual duplex gage 95. The pipe 96 connects the 110 other hand of the gage with the usual connection 51 of the main reservoir.

It is to be understood that with the construction shown in Figs. 3 and 5 the connection 52 of Figs. 1 and 2 is closed, and therefore the only means for indicating pressure in train-pipe or equalizing-reservoir is through the passages and ports 92, 93, and 94. In Fig. 4 a small extension on the face of the valve from the cavity 37 toward the center 115 stands over port 92 with the valve in release. A passage 97 is drilled through the body of the valve 5 into cavity 37, the outer end thereof being plugged, and two ports 98 and 99 are then drilled upward from the face of the valve 120 into said passage. Two small cavities 100 and 101 are also cut in the face of the valve, as illustrated.

The operation of Figs. 3 and 4 is as follows: 125 The valve 5 being placed in position upon the 130

seat 6, when the handle is in release position the port 27 stands over port 30, admitting pressure directly into the train-pipe, and when the valve is in the two running positions the port 27 stands over ports 33 and 43, respectively, through which the compressed air is admitted into the pressure-reducing valves and thence by the passages 35 and 44 into train-pipe cavity 18, as fully set forth in my said prior patent. With the usual gage-pipe connected at 52 of Figs. 1 and 2 the gage really indicates reservoir-pressure, and this will be the same as train-pipe pressure only when train-pipe and reservoir are in communication. With the valve 5 in any position for admitting air into train-line the cavity 37 connects both ports 42 and 90 with the port 92, leading through 93 and 94 to train-line gage, so that both train-line and reservoir-pressures are indicated on the gage. To apply brakes, the valve is turned to service position, releasing air from the upper side of the piston and reservoir until there is a five or ten pound reduction, when the valve is returned to lap. It is desirable that in both service and lap positions of the valve all communication between reservoir and train-pipe—that is, between the upper and the lower sides of the piston—shall remain cut off. If the train-line hand of the gage is connected at 52, as heretofore practiced and seen in Figs. 1 and 2, it is evident that in service and lap positions of the valve the gage-hand will indicate reservoir-pressure and not train-line pressure. If the engineer through error leaves the valve-handle on lap, the gage, which in running position of the valve indicates train-line pressure, will indicate reservoir-pressure, and therefore if there is a leak of pressure into reservoir or the piston fits its chamber accurately the air from the train-pipe may leak away, while that in the equalizing-reservoir remains substantially constant or increases and indicates to the engineer that he is carrying on his train a pressure much greater than that which he is really carrying. This has been known to happen in practice, with the consequence that when the engineer moves the valve to service position and reduces the reservoir-pressure the usual amount he gets no response from the brakes, because the train-line pressure has leaked away without indicating that fact on the gage. With my improvements, Figs. 3 and 4, the above error cannot happen. As already noted, in release and running positions cavity 37 in the valve connects ports 42, 90, and 92, and therefore the train-line hand of the gage will indicate the pressure in both train-pipe and reservoir. When the valve is moved to service position, the port 98 stands over the outer and lower portion of channel or groove 91, the port 99 remains blanked, the cavity 100 stands over port 42, but communicates with nothing else, and the cavity 101 in the valve-face connects the inner end of channel 91 with port 92.

In service position of the valve, therefore, pressure from the reservoir and the upper side of the piston passes to the gage through ports and passages 90, 37, 97, 98, 91, 101, 92, 93, and 94. As fully explained in my said prior patent, the port 42—that is, the train-pipe—is at this time out of communication with port 90. In service position of the valve, therefore, the gage-hand connected with the pipe 94 indicates reservoir-pressure only and enables the engineer to gage the amount of reduction which he is making from the reservoir and the upper side of the piston. Having reduced the pressure to the extent desired in the reservoir, the engineer returns the valve to lap position, when the port 98 passes below or out of communication with channel 91, while cavity 100 now connects port 42 with said channel, and cavity 101 still keeps said channel in communication with port 92. Reservoir-port 90 is now shut off from the gage, while the pressure from the port 42, or train-pipe pressure, passes to the gage through ports and passages 42, 100, 91, 101, 92, 93, and 94, and the gage-hand therefore indicates train-line pressure. When the valve is moved to emergency position, the port 98 registers with port 42, while port 99 registers with port 92, so that train-pipe pressure passes to the gage through ports and passages 42, 98, 97, 99, 92, 95, 93, and 94. If the inner arc of cavity 37 is made long enough to still remain above the port 90 while the valve is in emergency position, the gage will indicate both reservoir and train-pipe pressures. It will be seen, therefore, that in all positions of the valve for admitting air into the train-pipe the gage-hand connected with the pipe 94 indicates both reservoir and train-pipe pressures. In service position it indicates reservoir-pressure, in lap position it indicates train-pipe pressure, and in emergency position it indicates either train-pipe or both train-pipe and reservoir pressures.

In Figs. 5 and 6 are shown modifications for accomplishing the results above described with reference to Figs. 3 and 4. When the valve 5 is placed on the seat 6 of Fig. 5 and moved to either position for admitting air from main reservoir into train-pipe, the pressure in the cavity 29 is admitted through the port 92 and passage 93, and the appropriate pipe to the gage-hand. Port and passage 92 and 93 correspond in function with those similarly numbered in Fig. 3 and are to be connected with the gage in the same manner. When the valve is moved to service position, cavity 29 passes beyond port 92, while cavity 102 on the valve-face connects port 36, leading to the reservoir, with port 92, and therefore reservoir-pressure reaches the gage through 36, 102, 92, 93, and the appropriate connections. As the valve is returned to lap position the cavity 102 passes below port 92, while cavity 29 connects train-pipe port 30.

with gage-port 92, and therefore train-pipe pressure is indicated on the gage. When the valve is moved to emergency position, the cavity 102 connects ports 36, 92, and 30, so that both train-pipe and reservoir pressures are indicated on the gage.

From the above descriptions it is apparent that the engineer may know at all times by means of a single gage-hand the exact conditions of pressure existing in both train-pipe and equalizing-reservoir and on both sides of the equalizing-piston and may control that piston with perfect certainty of operation, causing it to move to the proper position when it is desired to vent the air from train-pipe to set the brakes and holding it in position to close the train-pipe vent at all times of admitting pressure into the train-pipe.

I claim—

- 20 1. In an engineer's brake-valve, the combination, with an equalizing-piston, an operating-valve and a pressure-indicator, of passages from said indicator to opposite sides of said piston alternately opened and closed by the operating-valve as it moves between service and lap positions.
- 25 2. In an engineer's brake-valve, the combination, with an equalizing-piston, an operating-valve and a pressure-indicator, of passages from said indicator to the reservoir and train-pipe sides of said piston, alternately opened and closed by the movement of the operating-valve as it occupies service and lap positions, respectively.
- 30 3. In an engineer's brake-valve, the combination, with an equalizing-piston, a pressure-indicator and passages from said indicator to the reservoir and train-pipe sides of said piston, of an operating-valve for successively opening the reservoir-passage while in service position and the train-pipe passage while in lap position.
- 35 4. In an engineer's brake-valve, the combination, with an equalizing-piston, a pressure-indicator and passages from said indicator to the reservoir and train-pipe sides of said piston, of an operating-valve for successively

opening, 1, the train-pipe passage, 2, the reservoir-passage and, 3, the train-pipe passage, while occupying, 1, running position, 2, service position and, 3, lap position, respectively.

5. In an engineer's brake-valve, the combination of an equalizing-piston in a chamber, a controlling-valve for admitting pressure to a train-pipe and to both sides of said piston and means arranged in connection with the train-pipe and piston-chamber whereby pressure may be admitted into the train-pipe more rapidly than to the train-pipe side of said piston.

6. In an engineer's brake-valve, the combination of an equalizing-piston in a chamber, an operating-valve for admitting pressure to a train-pipe and to both sides of said piston and means controlled by the flow of pressure toward the train-pipe for preventing the piston from moving to open a train-pipe vent.

7. In an engineer's brake-valve, the combination of an equalizing-piston, a controlling-valve for admitting pressure to equalizing-reservoir and train-pipe and a passage from train-pipe to one side of said piston so arranged that pressure admitted to the train-pipe tends to create a draft or suction through said passage away from said piston.

8. In an engineer's brake-valve, the combination, with an equalizing-piston, a pressure-indicator, passages from said indicator to the reservoir and train-pipe sides of said piston, an operating-valve for controlling said passages so as to admit reservoir or train-pipe pressure to the indicator accordingly as said valve is respectively in service or lap position, and passages for admitting pressure to the train-pipe and to both sides of said piston so arranged that, while flowing to the train-pipe, it tends to draw the pressure away from the train-pipe side of said piston by draft or suction.
